LOCKING DEVICE

William Edward Byrne, Los Angeles, Calif.

Application August 16, 1941, Serial No. 407,150

4 Claims. (Cl. 70—156)

This invention relates to locks which are adapted to be opened when struck at certain specific parts thereof. Key operable means are provided, however, for setting the lock in a neutral position so as to permit the lock to automatically open when a certain part thereof is broken, but which is adjustable in two other positions: one of which opens the lock without the breaking or releasing of a part thereof, and another position in which the lock is maintained locked even though a part thereof is broken, dented or otherwise forced out of alignment.

Such locks are adapted for a number of uses but it is believed that the outstanding use for the lock is upon fire doors in apartment houses, theatres, hotels and transportation vehicles. In some installations, it would be advantageous to connect an alarm system with the locks so that when one is opened, a bell or other signal is operated to let certain persons or all persons know that the lock has been opened. When installed on fire doors in public houses, it might be best to arrange the lock and signal system to give a general alarm when opened.

The part of the lock housing to be broken may comprise any brittle substance such as glass. The glass is mounted upon the lock housing in a manner so that it can easily be replaced when the lock is reset.

An object of the invention is to provide a locking device adapted to be automatically unlocked when a certain specific part thereof is struck.

Another object is to provide a locking device which has a plurality of functions: a setting permitting unlocking thereof when a certain part of its shell or housing is broken, an operation which unlocks the device without the breaking of any part thereof and holds the same unlocked, if desired, and another operation which locks the device and maintains it locked whether or not the shell thereof is broken. Whenever the device is locked or unlocked, it may be switched to the setting above mentioned so as to be set for automatic unlocking when the certain part of its shell is broken.

Other objects, advantages and features of my invention will appear from the accompanying drawings, the subjoined detailed description, the preamble of these specifications and the appended claims.

Applicant has illustrated and described one or more forms of his invention in order to teach one how to make, use and vend the same, but it is to be understood that the drawings and description thereof are not to limit the invention in any

sense whatsoever, except as limited by the appended claims.

In the drawings:

Fig. 1 represents the invention in partial phantom view from the top thereof, a part thereof being broken away for clarity.

Fig. 2 shows a plan view of the lock in Fig. 1 with the cover and keeper removed.

Fig. 3 shows a side elevation of the lock without the cover and keeper.

Fig. 4 shows a section of the lock taken substantially along the line 4—4 of Fig. 2.

Fig. 5 shows a section of the lock taken substantially along the line 5—5 of Fig. 1.

Fig. 6 shows another phantom view of the lock from the top thereof.

Fig. 7 shows an elevation of the lock cover with a part thereof broken away.

Fig. 8 shows a section of the cover substantially along the line 8—8 of Fig. 7, and

Fig. 9 shows another phantom view of the lock from the top thereof.

The numeral 1 represents a cover of a locking device and 2, the keeper. The keeper may be screwed or otherwise secured and fixed to the jamb of the doorway in any suitable manner known to those skilled in the art. Beneath the cover 1 is a base plate 3 which carries the locking mechanism and is held to the door upon which it may be mounted by screws which pass through the holes 4 thereof. The cover has a top wall 5, side depending walls 6 and 7, and end depending walls 8 and 9, all joined to form an integral unit. Screws 10 pass through holes in the end wall 9 of the cover and have threaded engagement with the tapped holes in the bosses 11 which are formed integral with the plate 3 or fixed thereto in any suitable manner such as by welding. This holds one end of the cover 1 securely to the base plate 3.

The end wall 9 is provided with a rectangular aperture 12, Fig. 7, through which reciprocates the tongue 13 of the sliding bolt 14. The bolt 14 is preferably one integral unit having side guides 15 and 16, and a relatively heavy end plate 17. Across the top thereof is a bar 18 predeterminedly positioned for a purpose to be explained later.

To one end of the plate 3 are guide bosses 19 and 20 which are integral with the plate or welded thereto. The bosses 19 and 20 are provided with machined flat surfaces 21 and 22 which oppose one another and are spaced from one another a sufficient distance to snugly receive one end of the sliding bolt 14, as shown. These bosses are provided with threaded holes 23 to receive screws

24 which pass through a part of the cover. The cover is perforated as shown at 25 and has integral therewith a recessed strip 26 which extends partially around the periphery of the opening 25, and which is provided with holes to accommodate the screws 24. By this construction, the screws 24 securely hold the cover to this end of the base 3.

The strip 26 has a protruded portion 27 which is integral therewith and which is offset below the bottom of the strip to act as an upper guide for the bolt end 17, as clearly shown in Fig. 4. The aperture 25 is closed by a member 28 which may be glass or any other brittle substance that can easily be broken by a sharp blow of a hammer. The glass 28 is held in the under rabbeted portion of a ring 29 which rests upon the strip 26 and also upon a protruded portion 30 of the cover top 5. The glass, therefore, is securely held between the tongue of the rabbet portion of the ring 29 and the strip 26 and also between the ring and the protrusion 30. Fixed to the underside of the ring 29, preferably integral therewith, is a trunnion-like element 31, having a cross pin 32 therebetween and fixed thereto, note Fig. 5. Across the underside of the ring is provided an offset tongue-like portion 33 which is integral therewith and adapted to slide under the top 5, as shown. In order to place the ring and its glass in the opening 25 of the cover, it is first necessary to slide the portion 33 beneath the periphery of the opening.

Fixed to the base plate 3 are trunnion-like supports 34 and 35 having pins 36 and 37 respectively as shown, see Figs. 2 and 5. These trunnions are adapted to receive a latching device such as the one indicated by 38 which has a hole to receive either pin 36 or 37 depending upon which trunnion it is desired to place the latch. The top of the latch device terminates in a hook like end 39 to snugly engage the pin 32. This latching device also has an offset portion 40 to be engaged by compression spring 41. Both inner sides of the trunnions 34 and 35 have slightly rounded recesses 42 and 43 respectively to provide a track to hold the spring 41. When the ring 29 is latched to the detent as shown clearly in Fig. 5, it can not be released without first breaking the glass.

By having the two trunnions 34 and 35, the ring 29 may be turned around in the opening 25 of the cover so that any reading placed on the outside thereof can be arranged in proper upright position so as to be clearly read. The reading matter on the outside of the ring may include the following: "In case of fire," at the top thereof, and "Break glass," at the bottom thereof. This clearly indicates how the door, to which the lock is attached, can be opened.

In order to resiliently float the bolt 14 upon the plate 3 so that it can reciprocate between the guides 21 and 22, a semi-cylindrical bossed portion 44 is placed upon the plate 3 as shown, note Fig. 2, and it is preferably integral with the plate. Both ends of the bore of the element 44 are open, but the central part thereof has a thickened wall portion 45 to provide shoulders and to act as spring stops. In opposite ends of the bore are compression springs 46 and 47. The spring 46 continually urges the tongue 13 outwardly toward the right in Fig. 2, beyond the end of the plate 3. The spring 47 lies between the stop 45 and a shoulder 48 of a cam pin or plunger 49 which is configurated as shown best in Fig. 4. A piston-like portion 49' snugly en-

gages the wall of the bore in sliding contact and has a portion 49" inclined to act as a cam surface which merges into a push pin 51. A stabilizer pin 50 extends from the opposite end 5 of the position 49' and is concentric with the spring 47 and the bore. The push pin 51 engages the inner side of the end plate 17 of the bolt and continually urges the bolt away from the keeper 2.

The cylindrical element 44 has at one end thereof a conical shaped boss 52 which extends upwardly to a position substantially on a plane with the underside of the glass 28. This boss has a bore 53 centrally thereof to snugly receive a round pointed lock pin 54. The pin 54 has a recess 55 elongated as shown and deep enough to receive a cross pin 56 which has its ends fixed to the sides of the bore. This recess permits the pin to reciprocate vertically within certain predetermined limits and is so arranged that the upper end of the pin 54 can be in contact with the underside of the glass 28 while its pointed end is resting upon the surface of the push pin 51.

Whenever the glass 28 is broken, the pin 54 is free to rise and is forced upwardly by the cam surface of the element 49 because of the compressed condition of the spring 47, see Fig. 2. This action causes the push pin 51 to thrust the bolt 14 to the left, to the position shown in Fig. 6. The tongue 13, therefore, retracts from the keeper 2 allowing the door to which the lock is attached, to be opened.

In order to control the bolt of the lock so that it may be opened without breaking the glass and also so that it may be permanently locked even though the glass may be broken, the cover 1 is provided with a conical like boss 57, note Fig. 7, which has a bore 58 to receive a cylinder key locking mechanism 59 which may be termed the auxiliary lock. The particular cylinder lock employed is of little moment so long that it is operable and adapted to turn axially with respect to the bore 58 when released by key or other means such as a dial control.

The bottom of the lock has a triangular slot 60 diametrically across it to receive a bent up portion 61 of an arm 62 configurated as shown. Two legs of the arm, 63 and 64 are bored to receive screws 65 and 66 which engage threaded bores 67 in the cylinder lock. By this arrangement, the arm 62 will swing with the lock 59 when it is rotated. The cylinder lock is provided with the usual keyhole 68 to receive a key, not shown. The arm 62 may be swung to the neutral position, as shown in dotted lines of Fig. 1, so that the tongue of the bolt is free to leave the keeper when the glass 28 is broken. The arm may also be turned to the position shown in Fig. 6 so as to hold the bolt from the keeper. The rounded end of the arm acts against the bar 18 of the bolt when the lock 59 is turned to open the main lock. The arm may, however, be placed as shown in Fig. 9 so as to force the tongue 13 into the keeper. If left in this position, the arm will prevent opening of the lock even though the glass is broken.

A hammer 69, having a rounded head 70, is provided so that the glass 28 may be broken in case of emergency, thus permitting the door, to which the lock is attached, to be opened. The hammer is held to the cover of the lock by spring clamp 71 which is fixed to a side of the cover by the screw 72.

Having thus described my invention, what is

claimed as new and desired to be secured by Letters Patent is:

1. In a lock device having a base and cover to be fastened to a door, and a keeper adjacent the device to be fastened to the side of a doorway, a bolt slideable in a guideway on the plate under the cover, the bolt having a tongue to enter and exit the keeper, a first spring urging the bolt toward the keeper, a breakable plate attached to the cover, a cam-pin engaging a portion of the bolt and a second spring for forcing the bolt away from the keeper, a cam surface on the cam-pin, a lock-pin engaging a lower portion of the cam surface and the under side of the breakable plate, said lock-pin adapted to move toward the plate when it is broken to release the cam-pin and force the bolt from the keeper to release the door and allow it to be opened.

2. In a lock device having a base and cover adapted to be fastened to a door, a chamber under the cover having means to provide a guideway, a bolt slideably positioned in the guideway, a tongue fixed to the bolt and adapted to be protracted from the chamber and retracted into the chamber, a first spring continuously urging the bolt in one direction to protract the tongue from the chamber, a cam-pin having a part thereof in contact with a portion of the bolt, a second and stronger spring urging the cam-pin in a direction opposite to the force direction of the first spring, a cam surface on the cam-pin, a breakable plate

attached to the cover, a lock-pin engaging a lower portion of the cam surface and the under side of the plate, said lock pin moving to release the cam-pin when the plate is broken and allowing the second spring to force the tongue into the chamber.

3. The device recited in claim 2 wherein the breakable plate is provided with a frame about the periphery thereof, said frame having fixed to the underside thereof a pair of latching elements, said elements being substantially diametrically opposite each other, one of the elements having an offset portion to engage the underside of the lock cover and the other element having a cross-pin fixed thereto, a spring controlled latching device anchored to the base and having a hook adapted to engage the cross-pin and lock the plate onto the cover.

4. The device recited in claim 2 wherein the bolt is provided with a pair of spaced apart cross-bars, a lock attached to the cover and having a key controlled rotary part thereof extending into the chamber, an arm fixed to the rotary part and positioned between the said bars, said arm pressing against one of the bars to move the bolt when turned in one direction, said arm preventing any movement of the bolt when the longitudinal axis of the arm is parallel with the longitudinal axis of the bolt.

WILLIAM EDWARD BYRNE.
